US0D1066267S

(12) **United States Design Patent** (10) **Patent No.:** **US D1,066,267 S**
(45) **Date of Patent:** **** Mar. 11, 2025**

(54) **FUSE CUTOUT**

(71) Applicant: **GOODWELL ELECTRIC CORPORATION**, Taipei (TW)

(72) Inventor: **Sui-Chan Kao**, Taipei (TW)

(73) Assignee: **GOODWELL ELECTRIC CORPORATION**, Taipei (TW)

(**) Term: **15 Years**

(21) Appl. No.: **29/819,483**

(22) Filed: **Dec. 15, 2021**

(30) **Foreign Application Priority Data**

Nov. 17, 2021 (TW) 110306235

(51) **LOC (15) Cl.** **13-03**

(52) **U.S. Cl.**

USPC **D13/161**

(58) **Field of Classification Search**

USPC D13/129, 132, 133, 149, 158, 160, 161, D13/178

CPC H01H 31/023; H01H 31/12; H01H 31/127; H01H 31/28; H01H 85/0241; H01H 85/08; H01H 85/165; H01H 85/2045; H01H 85/38; H01H 2085/381; H01H 2085/383

(57) **CLAIM**

The ornamental design for a fuse cutout, as shown and described.

DESCRIPTION

FIG. 1 is a top, front and left side perspective view of a fuse cutout showing my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the article that form no part of the claimed design.

1 Claim, 7 Drawing Sheets
